UNITED STATES PATENT OFFICE

164,501

STORAGE CABINET OR SIMILAR ARTICLE

William Jameson, Miami, Fla.

Application October 13, 1950, Serial No. 12,552

Term of patent 14 years

(Cl. D33—19)

To all whom it may concern:

Be it known that I, William Jameson, a citizen of the United States, residing at Miami, county of Dade, and State of Florida, have invented a new, original, and ornamental Design for a Storage Cabinet or Similar Article, of which the following is a specification, reference being had to the accompanying drawing, forming a part thereof, in which:

Figure 1 is a front elevational view of a storage cabinet or similar article showing my new design; Fig. 2, an end elevational view, the ends of the cabinet being alike; Fig. 3, a top plan view; and Fig. 4, a vertical sectional view.

I claim:

The ornamental design for a storage cabinet or similar article, as shown.

WILLIAM JAMESON.
